Application May 22, 1936, Serial No. 81,171

2 Claims. (Cl. 285—22)

Our invention relates to casing heads used at the upper ends of wells for the purpose of closing and supporting the upper ends of separate strings of pipe or casing which are extended down into the well.

In the drilling of oil wells and the completion of the well structure after drilling, strings of pipe or casing are placed one within the other, and after the completion of the well it is generally customary to extend an oil string down into the well structure through which the production of the well is carried to the surface of the ground. Our present invention provides a simple and effective means for hanging or supporting these various strings of casing, piping, or tubing in the well and for closing the upper ends thereof so that the pressures within the separate strings may be controlled. Some of these strings are cemented in the well, and in such case the casing head serves the mere purpose of closing the upper ends of the spaces around the cemented strings.

It is an object of the invention to provide a casing head of improved form by which the upper end of one pipe string may be supported and sealed at or within the upper end of another pipe string, this casing head having a simple duplex sealing means employing in combination a gasket seal of soft material and a metal-to-metal seal. In the preferred form of the invention we employ a grooved fitting at the upper end of the pipe string, a solid compression and sealing ring, and a split ring for connecting the solid ring to the grooved fitting so that the weight of the inner string of pipe may be transmitted from the fitting to the solid ring which not only compresses the soft packing ring but also makes a metal-to-metal seal with a sealing face provided for this purpose by the shell of the casing head. The sealing means above described not only seals around the upper end of the inner string but also seals off the space above the sealing ring.

A further object of the invention is to provide a casing head which may be used not only in the ordinary manner of casing heads, but also may be used, owing to the characteristic construction thereof, in connection with slips for the supporting of the inner string while it is being lowered or raised within the outer string.

Further objects and advantages of the invention will be made evident throughout the following part of the specification.

Referring to the drawings, which are for illustrative purposes only,

Fig. 1 is a vertically sectioned view showing a preferred embodiment of our invention.

Fig. 2 is a cross section on a plane represented by the line 2—2 of Fig. 1.

Fig. 3 is a vertically sectioned view of an alternative form of our invention employing a screw

cap for closing the sealing means, instead of the bolted clamping ring shown in Fig. 1.

Fig. 4 is a view showing how the form of casing head or shell disclosed in Fig. 3 may be employed with slips to hold the pipe string during its installation or removal, or with a tubing supporting sleeve having the packing compressing ring integrally formed thereon.

Fig. 5 is an enlarged fragmentary section through the compressor ring shown in Fig. 1. 10

Fig. 6 is a sectional view illustrating the manner in which a plurality of the supporting and sealing units are associated in order to support three or more casings or tubings in a well.

As shown in Figs. 1 and 2, the casing head 15 provides a shell or body 10 having a cylindrical wall 11, the lower end of which is provided with threads 12 whereby it may be attached to a pipe or casing string 13 which extends within the well. The body 10 is enlarged at its upper end to provide an enlarged portion 14 from which a circular flange 15 extends radially. The enlarged portion 14 is provided with a counterbore 16 forming a packing recess for receiving a ring 17 of what may be termed "soft packing". This ring 17 may

be made from a material somewhat plastic in its nature which will expand in radial direction when placed under axial compression. A material suitable for this purpose is rubber or rubber compound. The counterbore 16 is defined by a cylindrical wall 18 and a bottom wall 19, a portion of which bottom wall is relieved so as to provide a conical face 21. At the upper end of the cylindrical wall 18 a conical seat 22 is formed. To compress the packing ring 17 a compressor ring 23 is provided which has a lower portion 24 of substantially the same radial dimension as the counterbore 16 and is adapted to project downwardly into the upper end of the counterbore 16 25 so as to compress the packing ring 17. Above the lower portion 24 the ring 23 is provided with a radial rib 25 having a lower conical face 26 and an upper conical face 27. The upper portion of the ring 23 is provided with an annular recess or counterbore 28 adapted to receive the outer portions of split ring segments 29 which are 30 adapted to engage an annular groove 31 in a sleeve coupling 32. The lower end of the sleeve coupling 32 is provided with internal threads 33 for engagement with threads 34 on the upper end of a pipe string 35 which extends downwardly through the bore of the body 10 and within the casing string 13 to which the body 10 is secured, as shown in Fig. 1. The external face 36 of the supporting member or coupling 32 is of 35 such diameter that it will just pass within the bore 37 of the body 10. The face 36 therefore defines the inner wall of the counterbore or recess 16 which receives the packing ring 17. The ring segments 29 form a separable flange for the 40

coupling 32 through which the downward load carried by the coupling 32 is transmitted to the compressor ring 23. The downward movement of the compressor ring 23 produces a compression of the packing ring 17 so that it will be expanded against the outer face 36 of the coupling 32, before the conical face 26 comes into engagement with the conical seat 22 of the body 10. The weight of the inner string 35 is transmitted 10 to the coupling 32 through the threads 34 and 33, and the load of the inner string is then imparted through the shoulder 38 of the coupling 32 to the ring segments 29 which in turn engage the upwardly faced shoulder 39 at the lower end 15 of the counterbore 28 of the compressor ring 23. Threaded into the body 10 below the packing 17 are lateral outlet pipes 40 which communicate with the interior of the outer casing 13 through the space 53 of the body 10.

20 The compressor ring 23 is forced downwardly with positive pressure against the seat 22 by means of a clamping ring 41 having a flange 42 which is forced toward the flange 15 of the body 10 by bolts 43. The member 41 has an upstanding cylindrical wall 44, and at the inner edge of the lower face 45 of the flange 42 a conical seat 46 is formed for engagement with the upper conical face 27 of the compressor ring 23. The downward pressure of the bolts 43 is transmitted 25 through the conical seat 46 of the clamping member 41 to the conical face 27 of the compressor ring 23. Within the lower part of the cylindrical wall 44 above the compressor ring 23 is an inwardly extending rib 47 having a 30 downwardly faced shoulder 48 for limiting the upward movement of the ring segments 29 should the coupling 32 be moved upwardly. The upwardly extending cylindrical wall 44 of the clamping member 41 is provided with threads 49 35 and 51 to which additional elements of the well structure may be secured, such, for example, as a nipple 52 which may be employed to support an additional casing head of the type shown in Fig. 1, or as shown in Figs. 3 and 4, for carrying another string of pipe which is to extend 40 downwardly within the pipe string 35.

45 The space between the compressor ring 23 and the outer face of the coupling 32 is effectively sealed by the soft packing ring 17. The space around the exterior of the ring 23 is sealed by the engagement of the face 26 with the seat 22 and the face 27 with the seat 46. Accordingly, the upper end of the space 53 is sealed not only by the soft ring 17 but by the metal-to-metal engagement of the face 26 with the conical seat 22. The lower end of the space 54 within the nipple 52 is sealed by the packing ring 17 and by the metal-to-metal engagement of the face 27 with the seat 46. The packing ring 17, when 50 compressed in place as shown in Fig. 1, has a lip 55 projecting downwardly into the conical space formed between the conical wall 21 and the outer face 36 of the coupling 32. This lip may be formed by the material of the packing 55 ring flowing into the conical space, or where the ring is molded from rubber the lip 55 may be formed thereon.

56 In many instances it may be desirable to provide auxiliary sealing means consisting of a 60 packing ring 56, the lower and upper portions of which extend respectively into annular grooves 57 and 58 in the confronting faces of the flanges 15 and 42. This packing ring 56 is disposed in the space between the compressor ring 23 and 65 the bolts 43.

70 In Fig. 1 we have shown the form of our invention especially adapted for use where it is desired to mount an additional casing head thereon. As shown in Fig. 3, the same principles of construction may be embodied in a casing head having a screw-type clamping means instead of a bolted clamping means, which casing head is especially suitable for supporting the final piping or tubing string. In this form of the invention a casing or body 60 is provided 75 which is similar to the body 10 shown in Fig. 1 with the exception that it has, instead of the flange 15, external threads 61 adapted to be engaged by the internal threads 62 of a screw-type clamping ring 63 comprising a cylindrical 80 wall 64 having an inwardly extending flange or lip 65 for engaging the ring segments 29 by which a coupling 32 is supported so as to carry an inner pipe string 35. The ring 63 may be provided with a pair of extending arms or lugs 85 85 by which it may be turned for the purpose of tightening it down on the threads 61 or unscrewing it. The inwardly extending lip 65 engages the upper faces 67 of the ring segments 29, and the downward pressure exerted by the clamping ring 63 is transmitted through the ring segments to a compressor ring 68 which differs from the compressor ring 23 in that it has only one conical face 69 for metal-to-metal engagement with the conical seat 71 formed in the counterbore 16a intermediate the upper and lower ends 90 of the counterbore. The lower part 72 of the counterbore is of smaller diameter than the upper part 73 of the counterbore, and the lower part 72 forms the recess for the soft packing ring 35 95 17. In this form of the invention the piping which extends upwardly from the packing head is screwed into threads 74 in the upper part of the coupling 32.

100 As shown in the left half of Fig. 4, the ring segments 29 and the compressor ring 68 shown in Fig. 3 may be replaced by a solid ring 80 which is formed integrally with a sleeve or fitting 81 adapted to support a tubing string 82. The ring or flange 80 of the fitting 81 extends 105 downwardly into an upper counterbore 83 in a body or shell 84, and compresses a soft packing member 85 into a lower counterbore 86. Between the upper and lower counterbores 83 and 86 a conical seat 87 is formed against which the ring 80 finally comes to rest after compression 110 of the packing ring 85. The screw-type clamping ring 63, shown in Fig. 4, bears downwardly against the upper face of the ring 80 and positively presses the same downwardly into its 115 proper position of use shown in Fig. 4. The upper end of the fitting 81 has external threads 88 and 89 to which either an outer pipe 91 or an inner pipe 92 may be connected as shown. The invention also provides, in combination with 120 the counterbored body disclosed in Figs. 1 to 4, a means whereby slips may be used to support the inner pipe string during the lowering and raising thereof. As shown in Fig. 4, a plurality of socket segments 93 are provided which, when 125 fitted together in the counterbore consisting of the upper and lower counterbores 83 and 86, will form a conical socket face 94 for receiving tapered slips 95. Preferably, there need be only two of the socket segments, which may in this 130 case be made semi-cylindrical in form. Each of the segments 93 has an upper, large diameter, arcuate wall 96 with a downwardly faced shoulder 97 at the lower end thereof for engaging the bottom wall 98 of the lower counterbore 86 so 135 95

that the weight of the tubing indicated at 82a, which is transmitted through the slips 95 to the socket segments 93, will be in turn transmitted through the shoulder 97 to the body or shell 84 of the casing head. It will be readily seen that such socket segments can be applied to the counterbore 16 disclosed in Fig. 1 and to the counterbores 72 and 73 of Fig. 3.

This final part of the invention is especially suited for use with a casing head adapted to carry the pump tubing of a well structure, which pump tubing is ordinarily pulled at frequent intervals in order to replace worn parts of the pump supported at the lower end thereof. The structure shown in Fig. 4 not only provides means for hanging the tubing 82 in the well during the operation of the pump but also provides for the pulling of the tubing without necessity of procuring a separate spider and jacks to hold the tubing, since the slips 95 and the required socket means therefor may be readily applied to the upper end of the casing head body.

Referring to Fig. 6 we illustrate the manner in which three or more casings, such as the outer casing 13 and the inner string 35, illustrated in Fig. 1, and an auxiliary string 100, may be supported and sealed off in a well. In this embodiment of the invention we show an auxiliary shell 30 or body 101 adapted for positioning directly above the body 10, the shell 101 having a lower flange 102 and an enlarged portion 103 similar to the flange 15 and enlarged portion 14 of the body 10 and being adapted for securement thereto by bolts 104 substantially in the manner shown. The enlarged portion 103 is provided with a counterbore 105 having a relieved portion forming a conical seat 106, the counterbore being symmetrical with the counterbore 16 of body 10, so that the opposed conical seats 22 and 106 respectively engage the lower and upper conical faces 26 and 27 of the ring 23 to form a metal-to-metal seal between the body 10 and the auxiliary body 101.

The internal diameter of the shell or body 101 is such that when the tubing shown threaded to the upper end of the sleeve coupling 32 in Fig. 1 is removed, the body 101 extends downwardly over the upper end of the coupling 32 in the manner shown.

Directly above the sleeve coupling 32 lateral outlet pipes 107 are threaded into the body 101, so as to communicate with the interior of the tubing 35 through the coupling 32.

The upper end of the body 101 is provided with a radially extending flange 108 and an enlarged portion 109, in which is formed a counterbore 110 having a relieved portion forming a conical face 111.

The auxiliary casing or pipe 100 extends through the coupling 32 and is threaded into the lower end of a sleeve coupling 112, which coupling is identical in form to the coupling 32 except as to diameter, and has associated therewith a ring 113 and split ring segments 114 which are identical in form to the ring 23 and segments 29 associated with the coupling 32.

The ring 113 is adapted to compress a packing 116 within the counterbore 110 to seal the space between the coupling 112 and the body 101.

The ring 113 seats on a conical seat 117 provided on the body and is compressed thereon by a cap member 118 bolted thereto in the man-

ner shown and having a conical seat 119 engaging the ring to provide a metal-to-metal seal between the body 101, the ring 113, and the cap 118.

In this embodiment of our invention the packing ring 56 of Fig. 1 has not been shown but may be included in installations where it is deemed desirable to provide packing means in addition to the packing 17 and 116 and the metal-to-metal seals afforded by the rings 23 and 113 and their associated seating surfaces.

We claim as our invention:

1. A casing head of the character described, including: a body having means for connecting it to the upper end of a casing, said body having a vertical bore therethrough with a counterbore in the upper end of said bore and an upwardly and outwardly flared conical seat in the upper part of said counterbore; a tubular member substantially completely filling said bore of said body and extending within said bore past said counterbore so that a packing recess substantially closed at the bottom is formed at the lower part of said counterbore; a soft packing ring in said recess; a compressor ring extending downwardly into the upper part of said counterbore to compress said soft packing ring, said compressor ring having a conical face for sealing engagement with said conical seat after said soft ring has been compressed, and said compressor ring having an upwardly faced conical sealing face; and a clamping ring adapted to be secured to the upper end of said body, said clamping ring having an inwardly and downwardly faced conical seat adapted to make sealing engagement with said upwardly faced conical face of said compressor ring and to force the same positively downwardly to compress said soft packing and press said downwardly faced conical face thereof into sealing engagement with said upwardly faced conical seat of said body.

2. A casing head of the class described for use with an outer well casing and an inner string of tubing, said casing head having: a body adapted for connection to the upper end of the casing, said body having a vertical bore therethrough with a counterbore in the upper end of said bore, the bottom of said counterbore being beveled to taper downward toward said bore, and the upper edge of said counterbore being beveled to provide a conical seat; a tubular member adapted for connection with the inner string of tubing, said tubular member extending within said bore past said counterbore with sufficient closeness of fit with the bore to form a packing recess having a closed bottom at the lower part of said counterbore; a soft packing ring in said recess; a compressor ring extending downwardly into the upper part of said counterbore to compress said soft packing ring and wedge the ring into the beveled lower end of the counterbore, said compressor ring having a conical face for sealing engagement with said conical seat after said soft ring has been compressed, said compressor ring being dimensioned to fit said tubular member sufficiently close to completely close said recess, thereby entrapping the soft ring; and a clamping ring adapted to be secured to the upper end of said body and to force the compressor ring positively downward.
